UNITED STATES PATENT OFFICE.

GEORGE LASKER, OF CHICAGO, ILLINOIS.

WATER-TUBE BOILER.

Application filed July 9, 1923. Serial No. 650,517.

My invention relates to improvements in water tube boilers, and has for one of its objects the provision of baffle means whereby the heated gases are directed over the tubes in a predetermined manner.

Another object of my invention is to provide a boiler of the kind described in which the feed water is introduced at a point away from the hottest gases, thereby permitting any solid matter in said feed water to precipitate out.

The invention has among its other objects the production of a boiler of the kind described, which is simple, compact, reliable, efficient and satisfactory for use wherever found applicable.

Many other objects and advantages of the construction herein shown and described will be obvious to those skilled in the art from the disclosures herein given.

To this end my invention consists in the novel construction, arrangement and combination of parts herein shown and described, and more particularly pointed out in the claims.

In the drawing, wherein I have illustrated the preferred embodiment of my invention, 1 indicates the front wall of a boiler setting, 2 the rear wall and 3 the vertical side walls thereof. A bridge wall 4 is shown as being arranged intermediate the front and rear walls of the setting at the rear of the grate 5, and the customary fuel and ash doors and the like may be arranged in the setting, as desired.

Within the enclosing walls of the setting are arranged a plurality of drums, of which 6 indicates the front drum arranged at the upper front end of the boiler, 7 a rear drum arranged at the lower rear end of the setting, and 8 and 9 a pair of rear drums arranged one above the other, both of said drums being above the rear drum 7. The drum 8 is arranged below the level of the drum 6, while the drum 9 is arranged substantially at the same level as the drum 6.

The flue or stack 10 for the discharge of the spent gases is shown as located at the front of the boiler above the drum 6. A pair of banks of tubes 11 and 12, respectively, connect the drums 6 and 7, and a bank of tubes 13 connects the drums 6 and 8. Tubes 14 connect the drums 6 and 9, these tubes acting as

a superheater, and tubes 17 connect the drums 8 and 9. A steam-discharge outlet 15 communicates with the upper side of the drum 9 and feed water is preferably introduced by a pipe 16 into the lower portion of the drum 9, being partially heated by the dry steam discharged into the drum 9 by the pipe 14, said feed water flowing to the drum 8 through the pipes 17.

The gases at the region of the drums 8 and 9 are practically at their coolest temperature, so that there will be but little tendency of any caking of the solid matter in the water. Any such solids in the water, especially where foul feed water is used, may settle and precipitate out so that it may be drained from the drum 8 from time to time through the drain 18. A drain 19 is provided for the drum 7 as shown.

The banks of tubes are spaced apart quite a distance so as to permit the entrance of a person therebetween and access doors 20 are arranged in the setting to communicate with the spaces between the adjacent banks, as shown. Baffles are arranged to direct the heated gases over the tubes in a predetermined path, the baffle 21 extending from the bridge wall 4 along the bottom of the tubes 11 toward the front of the boiler, the baffle 22 extending from the front drum to adjacent the drum 7 on top of the tubes 11, the baffle 23 extending from the drum 7 on top of the tubes 12 to adjacent the drum 6, and the baffle 24 extending on top of the tubes 13 from the drum 6 to the drum 8. The top wall 25 of the setting forms substantially a baffle above the bank of the superheater tubes 14.

The heated gases arising from the fuel bed on the grate 5 will pass over the tubes in substantially the direction shown by the arrows in the drawing, such gases decreasing in volume as they move from their hottest point to their coolest point. The variation in volume of the gases is taken account of by varying the number of tubes in the various banks; that is, there are more tubes in the banks adjacent the hottest gases than there are in the bank over which the cooler gases pass, or in other words, there are more tubes in the bank 11 than in the bank 12, and more tubes in the bank 12 than in the bank 13.

The heated gases pass along the tubes in a

direction reverse to that in which the greatest proportion of the water flows in the tubes. For example, the path of the water in the lowest bank of tubes will be from the drum 7 to the drum 6, and the gases will flow in the opposite direction. The relation between the flow of water and the gases as regards the other banks will be the same as with the bank 11.

10 The feed water is partially heated in the drum 9, the same functioning as an economizer, this heat being increased during its passage through the pipes 17 into the drum 8. The heat at this portion of the boiler, 15 however, not sufficiently great to set up a violent circulation at this point and hence any solid matter in the feed water, especially where foul feed water is being used, is given a chance to precipitate out to the bottom 20 of the drum 8.

The water levels of the drums 6 and 9 may be maintained substantially at a common level, as these two drums communicate with one another. There are two complete 25 circulating units in the boiler, namely, the unit comprising the drums 6 and 7 and their connecting tubes, and the unit comprising the pair of drums 8 and 9, the drum 6 and their connecting tubes.

30 Having thus described my invention, it is obvious that various immaterial modifications may be made in the same without departing from the spirit of my invention; hence I do not wish to be understood as 35 limiting myself to the exact form, construction, arrangement and combination of parts herein shown and described, or uses mentioned.

What I claim as new and desire to secure 40 by Letters Patent is:

1. In a device of the kind described and in combination, a boiler having a front drum, a rear drum at the lower end of the boiler, tubes connecting said drums, a pair 45 of vertically spaced drums at the rear of said boiler above said rear drum, tubes connecting said pair of drums, tubes connecting each of said pair of drums directly with the front drum, said first-mentioned rear drum communicating with said pair of drums solely through said front drum, means for introducing feed water into the uppermost drum of said pair of drums, and a steam outlet from one of said drums.

55 2. In a device of the kind described and in combination, a boiler having a front drum, a rear drum at the lower end of the boiler, tubes connecting said drums, a pair of vertically spaced drums at the rear of said 60 boiler above said rear drum, tubes connecting said pair of drums, tubes connecting each of said pair of drums directly with the front drum, said first-mentioned rear drum communicating with said pair of drums solely through said front drum, means for intro-

ducing feed water into the uppermost drum of said pair of drums, and a steam outlet from said last-mentioned drum.

3. In a device of the kind described and in combination, a boiler having a front top 70 drum, a rear drum, tubes connecting said drums, a pair of vertically spaced rear drums above said first-mentioned rear drum, tubes connecting said pair of drums, tubes connecting each of said pair of drums with the front drum, means for introducing feed 75 water into the upper of said pair of drums, a steam outlet from said last-mentioned drum, an enclosure about all of said drums and tubes and having a flue at its top adjacent the front above said front drum, and baffles for directing the gases over said tubes in a predetermined manner.

4. In a device of the kind described and in combination, a boiler having a front top 85 drum, a rear drum, tubes connecting said drums, a pair of drums arranged one above the other at the rear of said boiler above said rear drum, an enclosure for all of said drums, the lower of said pair of drums being spaced 90 forwardly from the rear of said enclosure, tubes connecting said pair of drums, tubes connecting each of said pair of drums with the front drum, said first-mentioned rear drum communicating with said pair of 95 drums solely through said front drum, a steam outlet from the upper of said pair of drums, and means for admitting feed water into said last-mentioned drum.

5. In a device of the kind described and 100 in combination, a boiler having a front top drum, a rear drum, tubes connecting said drums, a pair of drums arranged one above the other at the rear of said boiler above 105 said rear drum, an enclosure for all of said drums, the lower of said pair of drums being spaced forwardly from the rear of said enclosure, tubes connecting said pair of drums, tubes connecting each of said pair of drums with the front drum, said first-mentioned rear drum communicating with said pair of 110 drums solely through said front drum, a steam outlet from the upper of said pair of drums, means for admitting feed water into said last-mentioned drum, and a flue in said enclosure 115 at its front above said front drum.

6. In a device of the kind described and in combination, a boiler having a front top drum, a rear drum, a pair of banks of tubes connecting said drums, a bridge wall intermediate said drums, a baffle extending along the bottom of the lower bank from the bridge wall toward the front of said tubes, a baffle on top of said lower bank of tubes from the front thereof to adjacent the rear 125 end, a baffle on top of the upper bank from the rear to adjacent the front end, a pair of drums arranged one above the other at the rear of said boiler above said rear drum, the lower of said pair being below the eleva- 130

tion of the front drum, an enclosure for all of said drums, the lower of said pair of drums spaced forwardly from the rear of said enclosure, tubes connecting said pair of drums, tubes connecting each of said pair of drums with the front drum, a baffle along the top of said last-mentioned bank of tubes from front to rear thereof, a steam outlet

from the upper of the rear of said pair of drums, means for admitting feed water 10 into said last-mentioned drum, and a flue in said enclosure at its front above said front drum.

In testimony whereof, I have hereunto signed my name.

GEORGE LASKER.
